UNITED STATES PATENT OFFICE.

EDWARD WYLDE, OF NEW YORK, N. Y., AND CHARLES SCHENCK, OF CHICAGO, ILLINOIS, ASSIGNORS TO ELEVATOR SUPPLY & REPAIR COMPANY, A CORPORATION OF ILLINOIS.

DOOR-CONTROLLING DEVICE.

1,090,370.

Specification of Letters Patent. Patented Mar. 17, 1914.

Application filed February 28, 1913. Serial No. 751,251.

To all whom it may concern:

Be it known that we, EDWARD WYLDE and CHARLES SCHENCK, citizens of the United States, residing at New York city, New York, and Chicago, Illinois, respectively, have invented certain new and useful Improvements in Door-Controlling Devices, of which the following is a clear, full, and exact description.

10 Our invention relates to a door-controlling device, and our object is to provide a construction which will prevent an unauthorized opening of the door when the same is not entirely closed.

15 Our invention will be set forth in the claims.

In the preferred embodiment of our invention, Figure 1 is a side elevation; Figs. 2 and 3 are details, and Fig. 4 is a modification.

20 1 is a door or gate, such as a slidable door which may be located along an elevator shaft at each floor, which when open gives access to the elevator car. In the embodiment shown we have provided automatic means for closing and latching the door. This may be of various constructions, but we prefer the arrangement shown in the drawings, which comprises an automatic 25 latching toggle operated by suitable actuating mechanism such as a spring-actuated dash-pot. The toggle comprises the levers 3 and 4 pivoted together at 5. Lever 3 is pivoted at 3^a, and lever 4 is pivoted to the door at 6. 30 The bent end 7 of lever 4 is connected to the hand-lever 9 by the link 8. The hand-lever 9 is pivoted at 10 to the door. When the lever 9 is thrown to the right the toggle will be broken and the door opened as indicated 35 in dotted lines.

40 The means for automatically closing the door may be a dash-pot 22 having a piston head 25 whose stem 2 is pivoted to the lever 3, as indicated.

45 22^a is a spring normally pressing the piston downward.

26 is a small air aperture which may be regulated by a valve 27.

50 It will be obvious that when the door is in its open position as indicated in dotted lines in Fig. 1, the spring will move the door to its closed position. A suitable latch is provided to hold the door closed and which

automatically operates when the door reaches its closed position. This may be a 55 pin 23 on lever 3 and slot 24 on lever 4, if desired, which causes the parts to remain in a position such that the toggle cannot be broken by a force applied merely to the door. 60 16 indicates the jamb of the door.

We have provided means for automatically stopping or checking the door against an accidental reverse movement during a portion of its closing movement. This may comprise two parts which are normally 65 freely movable past each other in either direction and which are inoperative to check the door when it is moved open from its completely closed position. In the present embodiment these two parts comprise a piv- 70 oted stop or detent 20 and a serrated surface 21. The weight of the detent 20 normally causes it to stand in the position indicated in Fig. 1. It will be obvious that when the door is moving to its closed position, it 75 will ride over the rack and on a reverse movement will engage the teeth and stop the door as indicated in Fig. 2. Just before the door comes to its closed position and the automatic lock operates, the pawl or detent 80 slips off from the last tooth of the rack and drops into the position indicated in Fig. 1.

As the door is given an opening movement from its closed position, the pawl is shifted and again rides freely over the rack as indicated in Fig. 3. It will be obvious that in the embodiment illustrated the pawl is released at each end of the rack and moves to a position such that it may freely ride over the rack but will stop the door if given an 85 opening movement from a point just short of its closed position.

In the modification shown in Fig. 4, there is provided a surface 21 and a pawl 20^a pivoted to the lever. This pawl is, like pawl 20, 95 adapted to engage the surface when the door is given an opening movement short of its closed position, as indicated in dotted lines. Similarly the pawl is released when the door is closed, as indicated in full lines, so that 100 the pawl freely rides over the surface on the next opening movement. The surface 21 is of such an extent that the pawl is similarly released when the door approaches its fully open position, so that the pawl does not prevent the door from freely shutting.

It will be observed that in the embodiment of the invention illustrated the latch which locks the door in its closed position operates to lock the door substantially at the same time as the pawl 20 is released from the rack 5. The pawl is also incapable of checking the opening movement after the latch has been released by breaking the toggle. In the embodiment illustrated we have shown the 10 latch so constructed that as the door moves to its closed position the latch is automatically and positively moved to its locked position by the movement of the door. This is of an advantage in some instances because it 15 tends to prevent the rebound of the door which sometimes occurs in the use of an ordinary spring-actuated latch on the jamb of the door.

We are aware that various modifications 20 of our invention may be provided without departing from the claims, and we therefore do not desire to be limited to the particular embodiment shown in the drawings.

What we claim is:

25 1. In combination, a door, automatic means for closing and latching the door, and an automatic stop for the door during a portion of its closing movement but inoperative on movement of the door from its 30 closed position.

35 2. In combination, a movable door, means automatically stopping said door against an opening movement at different points during a portion of its closing movement and comprising two parts, one of which is moved by the movement of the door, said parts being freely movable past each other and unengageable during the 40 closing movement but arranged to engage automatically and only when said door is given an opening movement from a point short of its closed position.

45 3. In combination, a movable door, means automatically stopping said door against an opening movement at different points during a portion of its opening movement and comprising two parts, one of which is moved by the movement of the door, said parts being freely movable past 50 each other and unengageable during the closing movement but arranged to engage automatically and only when said door is given an opening movement from a point short of its closed position, and automatic 55 mechanism for closing and latching the door.

60 4. A movable door, means automatically stopping said door against an opening movement at different points during a portion of its closing movement and comprising two parts, one of which is moved by the movement of the door, said parts being normally freely movable past each other during 65 a portion of the closing movement but arranged to engage automatically on a reverse movement of the door.

verse movement of the door, one of said parts being automatically moved into non-engageable relation to the other substantially as said door reaches its closed position.

70 5. A movable door, means for checking said door against an opening movement during a portion of its closing movement and comprising a surface, and a detent adapted to travel over said surface and check an accidental opening movement, said detent being so arranged that when the door is completely closed the detent automatically moves into a position to pass freely by said surface during the opening movement 80 of the door.

75 6. A movable door, an automatic latch for the door in its closed position, a detent, a surface to be engaged thereby, one of said parts being movable across the other by the movement of the door, said detent being arranged to engage said surface to stop said door against accidental opening during a portion of the closing movement of said door, one of said parts being automatically 90 movable, substantially when said latch operates, into a position such that the detent is inoperative to stop the door in its opening movement.

85 7. A movable door, means automatically 95 stopping said door against an opening movement at different points during a portion of its closing movement and comprising two parts, one of which is moved by the movement of the door, said parts being normally freely movable past each other during a portion of the closing movement but arranged to engage automatically on a reverse movement of the door, one of said parts being movable, when said door is completely closed, into such relation to the other part that said parts cannot engage during 100 the opening movement.

105 8. A movable door, means automatically stopping said door against an opening 110 movement at different points during a portion of its closing movement and comprising two parts, one of which is moved by the movement of the door, said parts being normally freely movable past each other during 115 a portion of the closing movement but arranged to engage automatically on a reverse movement of the door, one of said parts being movable, when said door is completely closed, into such relation to the other part 120 that said parts cannot engage during the opening movement, and a latch for the door positively moved to its latching position by the closing movement of the door.

125 9. A door, a latch for the door in its closed position, a stop automatically operating to check said door at different points against an opening movement during a portion of its closing movement, said stop being constructed and arranged to be inca- 130

pable of checking the opening movement after said latch has been released.

10. In combination, a door adapted to travel to an open position and to a closed position, a check device comprising two parts coöperating when effective to prevent an accidental opening movement of said door when closing, one of said parts being freely movable at all times and arranged to be rendered ineffective simply by the re-

versal of the direction of movement of said door at or about its closed position.

Signed at New York city, N. Y. this 31 day of January 1913.

EDWARD WYLDE.
CHARLES SCHENCK.
